UNITED STATES PATENT OFFICE.

ALFRED D. HARVEY, OF LANHAM, MARYLAND, ASSIGNOR OF ONE-FOURTH TO C. A. M. WELLS, OF WASHINGTON, DISTRICT OF COLUMBIA, ONE-FOURTH TO THOMAS H. WELSH, OF HYATTSVILLE, MARYLAND, AND ONE-TWENTIETH TO M. H. DUCKETT, OF LYON PARK, VIRGINIA.

VENDING MACHINE.

Application filed August 8, 1927. Serial No. 211,402.

This invention relates to vending machines and has special reference to a vending machine principally for use in vending newspapers although the same may be used to vend 5 magazines, pamphlets, and the like by minor modifications of the coin receiving apparatus.

One important object of the invention is to improve the general construction of devices 10 of this character.

A second important object of the invention is to provide improved means for bringing successive newspapers, magazines or the like 15 in position for delivery.

15 A third important object of the invention is to provide a novel arrangement of parts whereby the delivery of the articles will be readily accomplished, upon the machine being opened, through the force of gravity.

20 A fourth important object of the invention is to provide an improved coin receiving apparatus for use in connection with such a machine.

A fifth important object of the invention is 25 to provide a novel coin receiving apparatus which may be adjusted to operate with either a single coin or a number of coins in accordance with the price to be obtained for the article sold.

30 With the above and other objects in view as will be hereinafter apparent the invention consists in general of certain novel details of construction and combinations of parts hereinafter fully described, illustrated in the accompanying drawings and specifically 35 claimed.

In the accompanying drawings like characters of reference indicate like parts in the several views, and:

40 Figure 1 is a vertical section through the machine with one side plate of the elevator or carrier removed to show the interior thereof.

Figure 2 is a section on the line 2—2 of 45 Figure 1.

Figure 3 is a detail section on the line 3—3 of Figure 1, the operating gears and the dogs being omitted to avoid confusion of the parts.

50 Figure 4 is an enlarged detail view showing the operative connection between the door and lifting chain.

Figure 5 is a still further enlarged view of certain of these parts.

Figure 6 is a section on the lines 6—6 of Figures 4 and 5 to a greatly enlarged scale. 55

Figure 7 is a plan view of the coin mechanism and associated parts, the casing being shown in section.

Figure 8 is a detail section on the line 8—8 showing the parts removed from the casing. 60

Figure 9 is a detail side view partly in section of the coin mechanism in one position.

Figure 10 is a view similar to Figure 9 showing a second position of the coin mechanism. 65

Figure 11 is a side view of a portion of the casing showing the arrangement of the coin box and mechanism.

Figure 12 is a perspective view of a certain slide forming part of the coin mechanism. 70

Figure 13 is a detail showing a modified arrangement for use with several coins.

In the construction of the invention as here disclosed there is provided a casing having a 75 bottom 10, a front wall 11 and side walls 12. This casing also has a rounded top 13 so that rain will run off from the top. The rear wall of the casing is provided with a door 14, the door being provided with a suitable lock 15 to 80 prevent improper access by unauthorized persons, said door being of ordinary construction and arranged to swing open to afford access to the interior. Fixed to the front and rear walls of the casing adjacent but in spaced 85 relation with the side walls are vertical rack bars 16 and within the casing is an elevator or carrier 17 having a series of inclined plates 18 extending from its front to its rear and provided with suitable small anti-friction 90 rollers 19 so that newspapers or pamphlets placed on these plates from the rear when the door is open to the slides, will roll down toward the front. It is to be understood that this elevator is open at the front and rear, the 95 side walls being tied together below by certain shafts. On the front shaft 19' and rear shaft 20 are revolvably mounted gears 21 which mesh with the rack bars 16. Between the shafts 20 and 19 are other shafts 22 and 100 23 and on these shafts are mounted respectively a driving gear 24 and an idler gear 25 which freely revolve on said shaft. It is to be understood that this gear arrangement is at the bottom of the carrier on each side. 105 Fixed to the gear 24 is a sprocket 26 and ad-

adjacent the top of the casing is a cross bar 27. To this cross bar is fixed one end of a pair of sprocket chains 28 each of which extends downwardly from the cross bar around and beneath the sprocket 26 and then upwardly and over a sprocket 29 carried on a shaft 30 extending across the upper part of the casing. From the sprocket 29 the chain runs rearwardly and passes over a sprocket 31 carried on a shaft 32 and then downwardly in a suitable guide pocket between the respective rear rack bar 16 and the side wall of the casing, the downwardly extending portion of the chain carrying a weight 33 which is capable of adjustment by means of additional weights 34. At the front of the casing the wall 11 is provided with a delivery opening 35 and to the bottom edge of this opening is hinged a door 36 which tends to spring slightly open through the action of a spring 37 which only acts during the first part of the movement of the door 36, the door when thus sprung open engaging a heavier spring 38 which acts at this time as a stop. Adjacent the chain 28 is a guide 39 which prevents this chain from moving laterally and pivoted to each side wall just in front of the respective chain is a bell crank lever 40 having one substantially horizontal arm which carries a trip pawl 41 normally extending through the chain and through a slot 42 in the guide 39 and normally held in alignment with the horizontal arm of the lever 40 by a spring 43. The lever 40 also has a substantially vertical depending arm which is connected by a link 44 with a bracket 45 on the door 36. From an inspection of Figures 4 and 5 it will be seen that when the door 36 is pulled open against the action of the spring 38 the lever 40 is rocked and the dog or pawl 41 will slide down into the next link of the chain 28 and its end will slip through that link. Now, the door 36 is pulled open against the spring 38 but when the door is released the spring 38 is sufficiently strong to snap this door shut and at the same time operate the link and lever to raise the chain 28. It is to be understood that the carrier is well counterbalanced so that not much effort is required to lift it. As this part of the chain 28 moves upwardly it causes rotation of the sprocket 26 which, through the gears 24 and 23, actuate the gears 21 to roll upwardly on the racks 16 and thus lift the carrier. In this manner every time the door is closed the carrier raises a distance equal to the distance between adjacent plates 18 so that when the door is opened and a paper withdrawn the release of the door closes said door and places a second paper in position for withdrawal. In order to prevent rattling of the carrier idler gears or rollers 46 may be employed at the top. When the carrier is fully loaded the counterweights 33 and 34 may be assisted by coiled compression springs 47 at the start of the lifting, these springs, of course, losing their

lifting effect as they expand which is desirable since the removal of the papers one by one gradually lightens the weight of the carrier and its contents. In order to prevent backward movement of the carrier there is fixed on the shafts 19' and 20 the arms 48 carrying spring pressed dogs 49 which engage the rack bars 16 and which may be released from the rear of the machine by manipulating the wires 50 for the front dogs and the cross bar 51 for the rear dogs. 75

The door 36 in its closed position inclines upwardly and has a vertical lip 52 which carries a keeper 53 engaged by a latch end 54 formed on a certain lever connected with the coin operated mechanism. The lip 52 closes against an inclined cover portion 55 having a transparent window 56 through which may be observed the condition of the carrier so as to show whether or not there are papers therein. Above the door is a casing 57 carrying a name plate or instruction plate 58 and over these parts and the coin mechanism is arranged a hood 59. 85

The coin mechanism is located in a casing 60 mounted on the side of the main casing and projecting somewhat in front of the front plate 11. This casing 60 has a door 61 provided with the usual lock 62 so that access can be had thereto by proper persons for the removal of the coins. Extending through the front wall of the casing 60 is a guide plate 63 having inturned edges 64 and on this guide plate, between the inturned portion, slides a coin slide 65 having upturned ends 66 to form a finger grip. This coin slide has intermediate its ends a coin receiving slot or opening 67 which, when the coin slide is pulled outwardly, is exposed so that a coin may be placed thereon. The latch 54, previously referred to, is on the end of a bent lever 68 which extends laterally through a suitable opening in the side wall 12 of the main casing and then rearwardly so that it may be pivoted adjacent its rear end to a fulcrum bracket 69 fixed in the casing 60. The rear end of this lever projects upwardly as at 70 through a slot 71 leading rearwardly from the coin opening 67 and this rear end 70 is so inclined that when a coin is placed in the coin slot and the slide pushed in the coin will engage and depress the rear end 70 and thereby raise the latch 54 out of the keeper 53, a cover plate 71 holding the coin downward to permit this, 100 such coin being shown at C. 115

Secured to the front wall of the casing 60 is a spring stop 72 which permits the coin to pass rearwardly but catches the same and prevents its being again pulled out. A spring 73 urges the forward end of the lever 68 downwardly but yields readily to the action of the coin. 125

If it is desired to use the invention for papers of different value a slight modification 130

tion of the lever 68 and slide 65 may be made as shown in Figure 13. In this modification the opening 67^a is made sufficiently large to receive several coins C and in place of the 5 upturned end 70 there is provided a sliding arm 70^a secured in adjusted position on the rear end of the lever by a set screw 70^b. Thus, if the paper is to cost three cents, three 10 coins must be placed in the coin slide since if only two are placed therein the arm 70^a, which has been adjusted for three, will not be reached when the slide is pushed fully in and therefore the latch 54 will not be released. Obviously, if the paper is to cost 15 two cents or one cent the arm 70^a is moved to appropriate position to engage the rear coin of the two or the single coin.

In general the device is operated by drawing out the slide 65 and placing the proper 20 coin or coins in position. The slide is then pushed in whereupon the latch 54 releases from the keeper 53 and the door 36 springs slightly open. The purchaser then depresses the door, withdraws the paper which has 25 slid down ready to be grasped and releases the door which then springs up and closes ready for the next purchaser.

There has thus been provided a simple and efficient device of the kind described and 30 for the purpose specified.

It is obvious that minor changes may be made in the form and construction of the invention without departing from the material spirit thereof. It is not, therefore, 35 desired to confine the invention to the exact form herein shown and described, but it is desired to include all such as properly come within the scope claimed.

Having thus described the invention, what 40 is claimed as new, is:

1. In a vending machine, a casing having a delivery opening, a door hinged to the casing at one edge of the opening and normally closing the latter, a carrier movable in said 45 casing past said opening, vertical rack bars in said casing between which said carrier moves, gears on the carrier engaging said rack bars, and a step-by-step mechanism connected to said door and arranged to effect 50 step-by-step rotation of said gears.

2. In a vending machine, a casing having a delivery opening, a door hinged to the casing at one edge of the opening and normally closing the latter, a carrier movable in said 55 casing past said opening, vertical rack bars in said casing between which said carrier moves, gears on the carrier engaging said rack bars, intermediate gears carried by the carrier and meshing with the first gears, a sprocket chain arranged to rotate one of the intermediate gears, and a step-by-step mechanism connected to the door for effecting step-by-step movement of the chain.

3. In a vending machine, a casing having a 60 delivery opening, a door hinged to the casing

at one edge of the opening and normally closing the latter, a carrier movable in said casing past said opening, vertical rack bars in said casing between which said carrier moves, gears on the carrier engaging said rack bars, 70 intermediate gears carried by the carrier and meshing with the first gears, a sprocket wheel fixed to one of the gears, a sprocket chain having one end fixed above the carrier and led beneath the sprocket wheel and upwardly, 75 idlers at the upper part of the casing over which said chain runs to provide a depending end, counter-weights on said depending end, and a step-by-step mechanism connected to the door for effecting step-by-step movement 80 of the chain.

4. In a vending machine, a casing having a delivery opening, a door hinged to the casing at one edge of the opening and normally closing the latter, a carrier movable in said 85 casing past said opening, vertical rack bars in said casing between which said carrier moves, gears on the carrier engaging said rack bars, intermediate gears carried by the carrier and meshing with the first gears, a sprocket wheel fixed to one of the gears, a sprocket chain having one end fixed above the carrier and led beneath the sprocket wheel and upwardly, 90 idlers at the upper part of the casing over which said chain runs to provide a depending end, counter-weights on said depending end, a lever pivoted to said casing, a pawl carried by said lever to engage and disengage 95 said chain, and a link connecting said door and lever to tilt the lever with the pawl engaged and thereby actuate said chain.

5. In a vending machine, a casing having a delivery opening, a door hinged to the casing at one edge of the opening and normally closing the latter, a carrier movable in said 100 casing past said opening, vertical rack bars in said casing between which said carrier moves, gears on the carrier engaging said rack bars, intermediate gears carried by the carrier and meshing with the first gears, a sprocket wheel 110 fixed to one of the gears, a sprocket chain having one end fixed above the carrier and led beneath the sprocket wheel and upwardly, idlers at the upper part of the casing over which said chain runs to provide a depending end, counter-weights on said depending end, a step-by-step mechanism connected to the door for effecting step-by-step movement 115 of the chain, and pawls carried by the carrier for engagement with said rack bars to hold the carrier raised, said pawls being releasable to permit dropping of the carrier.

6. In a vending machine, a casing having a delivery opening, a door hinged to the casing at one edge of the opening and normally closing the latter, a carrier movable in said 120 casing past said opening, vertical rack bars in said casing between which said carrier moves, gears on the carrier engaging said rack bars, intermediate gears carried by the carrier and 125

meshing with the first gears, a sprocket wheel fixed to one of the gears, a sprocket chain having one end fixed above the carrier and led beneath the sprocket wheel and upwardly, 5 idlers at the upper part of the casing over which said chain runs to provide a depending end, counter-weights on said depending end, a lever pivoted to said casing, a pawl carried by said lever to engage and disengage said 10 chain, a link connecting said door and lever

to tilt the lever with the pawl engaged and thereby actuate said chain, and pawls carried by the carrier for engagement with said rack bars to hold the carrier raised, said pawls being releasable to permit dropping of the carrier. 15

Signed at Washington, D. C., this 8th day of August, 1927.

ALFRED D. HARVEY.
